UNITED STATES PATENT OFFICE

CHARLES W. COMSTOCK, OF DILLEY, OREGON, ASSIGNOR OF ONE-HALF TO RUFUS G. BAYER, OF NATICK, MASSACHUSETTS.

ROTARY VALVE.

1,248,080.

Specification of Letters Patent. Patented Nov. 27, 1917.

Application filed June 30, 1917. Serial No. 177,948.

To all whom it may concern:

Be it known that I, CHARLES W. COMSTOCK, a citizen of the United States, and a resident of Dilley, in the county of Washington and State of Oregon, have invented a new and Improved Rotary Valve, of which the following is a full, clear, and exact description.

The invention relates to internal combustion engines, and its object is to provide a new and improved rotary valve arranged to control the admission of the explosive mixture and the exhaust of the spent gases in an exceedingly simple, effective and practically noiseless manner, and to insure proper ignition of the charges.

In order to accomplish the desired result use is made of a valve body having a cylindrical bore provided with an inlet port, an exhaust port and two cylinder ports for each cylinder, one of the cylinder ports being in longitudinal alinement with the inlet port, and the other cylinder port being in longitudinal alinement with the said exhaust port, and a tubular valve mounted to rotate in the said valve body and driven from the engine shaft, the said valve having chambers, one for each cylinder, and provided with two ports one arranged alongside the other and adapted to register alternately with the sets of aligned ports in the said valve body.

A practical embodiment of the invention is represented in the accompanying drawings forming a part of this specification, in which similar characters of reference indicate corresponding parts in all the views.

Figure 1 is a side elevation of the rotary valve as applied to a 4-cylinder internal combustion engine, parts being shown in section;

Fig. 2 is a cross section of the same on the line 2--2 of Fig. 4;

Fig. 3 is a similar view of the same on the line 3--3 of Fig. 4;

Fig. 4 is a sectional plan view of the same on the line 4--4 of Fig. 3 and with the valve omitted; and

Fig. 5 is a plan view of the valve.

The improved rotary valve is shown applied to an internal combustion engine having four cylinders 10, 11, 12, and 13 in which reciprocate pistons 14, 15, 16 and 17 connected in the usual manner by pitmen 18 with cranks 19 of a crank shaft 20. The cranks 19 for the several pistons are ar-

ranged in the usual manner on the engine shaft 20 so that two of the pistons reciprocate simultaneously in one direction and the other two pistons travel simultaneously in opposite directions, as will be readily understood by reference to Fig. 1. The cylinder heads 21, 22, 23 and 24 for the several cylinders 10, 11, 12 and 13 are preferably in one casting together with a tubular valve body 25 having a cylindrical bore in which rotates a tubular valve 26. One outer end of this valve 26 is connected with the engine shaft 20 to rotate the valve 26 at the rate of 2 to 1 relative to the rotation of the engine shaft 20. The connection between the valve 26 and the engine shaft 20 may be of any desired type, such, for instance, as sprocket wheels 27 and 28 and a sprocket chain 29, but I do not limit myself to this particular driving means for the valve 26.

The valve body 25 is provided, for each cylinder, with two cylinder ports 40 and 41 disposed on opposite sides of the axis of the cylinder, as will be readily understood by reference to Figs. 2, 3 and 4. The ports 40 and 41 are not in transverse alinement, as plainly indicated in Fig. 4, and alongside the port 40 and opposite the port 41 is arranged an inlet port 42 connected by a pipe 43 with the manifold. Alongside the cylinder port 41 and opposite the cylinder port 40 is arranged an exhaust port 44 connected with an exhaust pipe 45. The cylinder ports 40 and 41 lead to the working chamber 46 formed in the head 21, 22, 23 or 24 of the corresponding cylinder 10, 11, 12 and 13. Each cylinder port 40 is provided with a spark plug 47 or other suitable igniting device.

The cylindrical valve 26 is provided with a chamber 50 for each cylinder, and each chamber 50 is provided with two ports 51 and 52 arranged one alongside the other. The port 51 is adapted to register successively with the ports 42, 41, and the port 52 is adapted to register successively with the ports 40 and 44.

The operation is as follows:

When the engine is running and the tubular valve 26 is rotating in the direction of the arrows (see Figs. 2 and 3) then the valve ports 51 and 52 first register with the ports 42, 40 to permit the explosive charge to pass from the manifold into the corresponding chamber 50 by way of the port 42.

- and then through the port 40 into the working chamber 46 of the corresponding cylinder at the time the piston therein is at the downward or suction stroke. During the 5 return stroke of the piston, the ports 51, 52 are in closed position and the charge is compressed in the cylinder and ignited, and when the piston reaches the end of its power stroke the ports 51, 52 move into register 10 with the ports 41, 44 so that on the return stroke of the piston the spent gases are forced out of the cylinder by way of the port 41, the corresponding chamber 50 and the port 44 which leads to the exhaust pipe 15 45. It is understood that the described operation of the valve is the same for each cylinder, only in the proper sequence, according to the successive impulses to be given to the pistons 14, 15, 16 and 17.
- 20 By reference to the drawings, it will be noticed that the valve body 25 and the cylinder heads 21, 22, 23 and 24 are provided with a common water jacket 60 connected at one end 61 with the radiator for circulating the water through the water jacket 60.

It will be noticed that by the arrangement described the admission of the explosive mixture to the working chamber and the exhaust of the spent gases is effected in a simple 30 and practically noiseless manner.

It will also be noticed that the rotary valve mechanism shown and described is exceedingly simple as it requires but a single bore in the valve casing and a single 35 tubular valve rotating in said bore to supply the several cylinders with the motive agent and to conduct the spent gases from the cylinder.

The valve mechanism shown and described 40 can be cheaply manufactured, and with the cylinder heads can be readily water cooled by making the valve body and the cylinder heads in one single piece.

Having thus described my invention, I 45 claim as new and desire to secure by Letters Patent:—

1. In an internal combustion engine, a cylinder provided with a working chamber, a piston reciprocating in the said cylinder, 50 a valve body having a cylindrical bore provided with an inlet port, an exhaust port and two cylinder ports, of which one is in longitudinal alinement with the said inlet

port and the other is in longitudinal alinement with the said exhaust port, and a tubular valve mounted to rotate in the said valve body and driven from the engine shaft, the said valve having a chamber provided with two ports one arranged alongside the other and adapted to register alternately with the said sets of longitudinally alined ports in the said valve body. 55

2. In an internal combustion engine, a cylinder provided with a working chamber, a piston reciprocating in the said cylinder, 60 a valve body having a cylindrical bore provided with an inlet port, an exhaust port and two cylinder ports, of which one is in longitudinal alinement with the said inlet port and the other is in longitudinal alinement with the said exhaust port, a tubular valve mounted to rotate in the said valve body and driven from the engine shaft, the said valve having a chamber provided with two ports one arranged alongside the other and adapted to register alternately with the 65 said sets of longitudinally alined ports in the said valve body, and an ignition device in the said cylinder port alined with the inlet port. 70

3. In an internal combustion engine, a plurality of cylinders, a valve body having cylinder heads formed thereon to close the said cylinders, the said valve body being provided with a cylindrical bore having a set of inlet ports, one for each cylinder, and connected with a manifold, a set of exhaust ports, one for each cylinder, and two cylinder ports for each cylinder, one cylinder port being alongside a corresponding inlet port 75 and the second cylinder port being arranged alongside the corresponding exhaust port, and a tubular rotary valve mounted to turn in the said bore and provided with spaced chambers one for each cylinder, each chamber having two ports arranged one alongside the other, the said ports in one position of the valve registering with the said inlet port and its adjacent cylinder port, and the said 80 valve ports in another position of the valve 85 registering with the said exhaust port and its adjacent cylinder port, and means for rotating the said valve from the engine shaft. 90

CHARLES W. COMSTOCK.
